LOCKING MEANS FOR JOINING SHEET MATERIAL

Marshall I. Williamson, Edgewater, N. J.

Application October 1, 1935, Serial No. 43,029

4 Claims. (Cl. 229—27)

My invention relates to locking means for joining sheet material, and to structure wherein the locking means are utilized in a novel manner.

More particularly, my invention relates to self-adjusting, coordinated locking means applicable to material such as paper, and other material possessing suitable stiffness in sheet form, and is particularly applicable to the manufacture of folding cartons, and the like, inclusive of displays adapted to contain merchandise or otherwise providing for special relationship of parts of the same.

Commercial embodiments of my invention, say of the folding carton type, embody complementary coordinated locking members usually having arcuate or other non-rectilinear contour, each member comprising both a male and a female element, the female element of one member being adapted to receive in coordinating relationship, the male member of the other and vice-versa, and the material of such male and female locking elements when assembled, as in setting up the carton or the like, effecting self-limiting adjustment of the thus assembled parts and also mutual bracing of the directly associated parts and therewith of the carton or the like as an entirety. My invention therefore enables the manufacture of folding cartons, displays, and the like, inclusive of compartmented structural forms of same, without the use of adhesive.

Advantageously, such male and female locking elements are had by slitting or otherwise contouring the sheet material at points wholly included by, and spaced apart from, its bounding edges, whereby each male element, upon slight pressing, is flexed free from its associated female element, and is thus prepared for insertion within and in interlocking relation with, the female element associated with the other male element.

Coincident with the mechanical advantages attending the various embodiments of my invention, the locking members may be variously contoured to form, for example, a heart or other outline bestowing decorative values to the resulting union of the locking member.

An understanding of the important features of my invention can be best obtained by considering a few of the various commercial embodiments in which it may appear.

In the accompanying drawings, the group of figures comprising Figs. 1, 2, 3, and 4 show my self-adjusting coordinated locking means as it may be employed as a fastener in the construction of a simple carton.

The group of figures comprising Figs. 5, 6, 7, 8, 9 and 10 show my locking means as it may be employed as a fastener in a carton having a more complex structure.

More particularly;

Fig. 1 is a perspective view, of a simple commercial carton formed of a single blank of sheet material, employing my locking means to keep it securely fastened in carton form.

Fig. 2 is a plan view of the outer face of the blank of the same carton, shown in Fig. 1, as it appears before folding into carton form, the individual male and female members of my locking means being clearly shown as they appear before inter-locking.

Fig. 3 is a perspective view of inter-locking sections of the carton shown in Fig. 1 with non-essential portions broken away. The individual locking members are shown ready for immediate inter-locking.

Fig. 4 is a horizontal section of a carton similar to that shown in Fig. 1 but having a trapezoidal cross-section rather than rectilinear.

Fig. 5 is a perspective view of a compartmented carton also formed of a single blank of sheet material, and employing my locking means to keep it and its integral partition securely fastened in carton form.

Fig. 6 is a horizontal section taken on the line 6—6 of Fig. 5.

Fig. 7 is a plan view of the inner face of the blank of the carton shown in Fig. 5, as it appears before folding into carton form.

Fig. 8 is a perspective view of interlocking sections of the carton shown in Fig. 5 with non-essential parts broken away. The material surrounding the male element is shown bent at right-angles on a line coincident with the base of the male member thus preparing the male member for insertion in the female member and at the same time forming an integral compartment wall which is buttressed against dislodgment within the carton when assembled.

Fig. 9 is a perspective view similar to that shown in Fig. 8 but having the locking means each contoured to form one half of a heart.

Fig. 10 is a side elevation looking in the direction of the arrow A in Fig. 9 and showing the ornamental configuration of a heart formed on an outer side wall of the carton, the locking members being in their locked position.

Referring to the drawings, and particularly to the figure group, comprising Figs. 1, 2, 3 and 4, the numeral 10, Fig. 2 indicates a blank stamped, or otherwise cut, from sheet material in such a

form and including such lineal impressions or scores as to prepare it for folding into a carton adapted to receive and retain suitable contents. The blank illustrated is of an ordinary simple type, and is shown with the usual integrally related, elementary carton elements marked off on its face by dotted lines.

With reference to both Fig. 1 and Fig. 2, the above mentioned carton elements include a front panel 11, which may have an indenture 11a located at its upper end to facilitate opening of the carton when the top is closed; a rear panel 12, having as an integral extension of its upper end, a closure member comprising a top panel 12a and an insert tab 12b, and as an integral extension of its lower end a similar closure member comprising a bottom panel 12c and insert tab 12d; an enclosed side panel 13, having as integral extensions of its upper and lower ends the closure-supporting flaps 13a and 13b respectively; an inter-locking side panel 14, having as integral extensions of its upper and lower ends the closure-supporting flaps 14a and 14b respectively; and a second inter-locking side panel 15.

Ordinarily such a blank as shown in Fig. 2, and above described, would be made up into carton form by suitably bending on the dotted lines, gluing the interlocking side panels 14 and 15 together, and closing the top and bottom in the usual well-known manner.

By use of my self-adjusting coordinated locking means, however, gluing, or the use of any adhesive, may be dispensed with entirely, and the finally assembled carton will still present a strong, tight, and well-secured joint as shown at 16, Figs. 1 and 4.

My locking means is composed of two individual inter-locking members such as shown at 17 and 18, Figs. 2 and 3, preferably of an arcuate or other non-rectangular contour; each of which, in turn, is composed of both a female element 17a and 18a respectively, and a male element 17b and 18b respectively, and is formed as an integral portion of its respective panel, in this case the interlocking side panel 14 or 15, by making an arcuate or other suitably contoured cut or slot in the material forming the panel.

These interlocking members, and component elements thereof, are preferably identical in contour with each other although necessarily so, only as to portions having a definite coacting relationship when in interlocked position, and have configurations directly opposed to each other. They are placed in their respective panels in such a manner that, when these panels are in the position assumed immediately prior to interlocking, the outer edge of one male member is directly opposed to, and is in proximate alignment with the outer edge of the other male element. This is well illustrated in Fig. 3.

The proximate alignment of these male elements when in the aforesaid position may be obtained by causing a slight planar displacement from their respective panels, and towards each other, of the outer edges of the male elements.

The planar displacement may be caused by gently pushing or punching the male elements so that their outer edges are out of planar coincidence with the surrounding panel material.

In order to complete the interlocking of the two panels, the planar displacement of the male element of each locking member is increased to such a degree that its associated female element, defined by the outer edge material of the male element and the inner edge of the imme-

diate adjacent panel material, is opened to an extent sufficient to admit the male element of the other locking member. The two panels are then slid across each other in such a manner and to such an extent that the juncture points of the male and female elements, as at 17c, 17d, of one locking member, are fitted tightly against the juncture points of the male and female elements, as at 18c, 18d, of the other locking member.

The permanence of the joint so formed will depend a great deal on the suitable tensioning or positioning of the panels which contain the individual locking members. To illustrate; the panels containing the joint 16 in Fig. 1 are so positioned with respect to each other, and to the remaining component carton structure, as to be secure against and resist any attempt to collapse the assembled carton by either pulling the front and rear panels in opposite directions, or by pushing them together. The only practical way the carton may be disassembled is by opening both of the end closures, flattening the body on the fold lines, and sliding the male elements out from coordinated relationship with the female elements. Thus the inherent tightness and securedness of the joint 16 can be readily appreciated.

The advantage of using my locking means as a fastening device for cartons can be most fully realized by noting its application to a carton having certain non-rectilinear polygonal forms, that shown in Fig. 4 having the geometrical form in cross-section of a trapezoid, but being in every other way similar to the one forming the subject of the above discussion, and having similar reference numerals for identical parts, with the addition, however, of a "prime" mark to each numeral.

In this particular type of box, because of its geometrical form and consequent location of fold lines, it is impossible to glue or otherwise permanently fasten the carton in its final form before shipping, and still retain the spacial shipping advantage of a collapsible flat form. However, if my locking means is employed as a fastening device, the carton may be shipped in the form of a blank and be easily set up in carton form at the point of ultimate utilization.

Referring now to the figure group comprising Figs. 5, 6, 7, 8, 9 and 10, and showing my locking means applied to one type of compartmented carton; the numeral 20, Fig. 7, indicates a carton blank, in many respects similar to that shown in Fig. 2, but having such an outline and such lineal impressions or scores as fit it for final assembly into a compartmented carton.

The various integrally related structural elements of the blank 20 in this particular instance include:—an exterior panel 21, having as an integral extension of its upper end, a closure portion consisting of a compartment top panel 21a and insert tab 21b, and as an integral extension of its lower end, a closure portion comprising a bottom panel 21c and an insert tab 21d; a second exterior panel 22 having as an integral extension of its upper end a closure portion consisting of a compartment top panel 22a and an insert tab 22b; an exterior, interlocking side panel 23 having as an integral extension of its upper end a medially split flap portion comprising the compartment-closure supporting flaps 23a and 23b, and as an integral extension of its lower end, the closure supporting flap 23c; a second exterior interlocking side panel 24 having

as an integral extension of its upper end a medially split flap portion comprising the compartment-closure supporting flaps 24a and 24b, and as an integral extension of its lower end the closure supporting flap 24c; an interior partition panel 25 having at its upper end the indenture 25a, and having as an integral extension of its lower end a closure portion consisting of the bottom panel 25b and insert tab 25c; an interlocking internal side panel 26; and a second interlocking internal side panel 27.

Positioned in the outer side panel 23 and at an edge of the interior partition panel 25 are individual members 28 and 29, respectively, of my locking means as shown and described in Fig. 2. Likewise, positioned in the outer side panel 24 and at an edge of the interior partition panel 25 are individual members 30 and 31, respectively, of another of my locking means.

These locking means are similar in nature and function to those shown in Fig. 2, with the exception that the individual members 29 and 31, have male elements which are prepared for interlocking, as in Figs. 8 and 9, by bending the surrounding panel material, at right-angles, on a line coincident with the base of the male element. In this way the interior partition panel 25 is firmly positioned between the exterior panels 21 and 22 to form the two compartments 32 and 33, Fig. 6, in the completely assembled carton.

The positioning of the panels, containing my locking means with respect to the other component parts of the carton, should be particularly noted. As clearly shown in Fig. 6, supplemented by reference to Figs. 8 and 9, the locking means, which serve to hold the partition panel 25 firmly in place, is secured against unlocking by the buttressing pressure-fit of the interior side panel 27 against the exterior panel 21.

Conceivably, a partition panel such as that shown at 25, and including individual locking members, might be made as a separate blank to be fitted when desired into coordinating locking members provided in an assembled carton. Also, a carton such as that shown in the first figure group might if desired, be formed of two separate blanks fastened together, in assembled form, by my locking means.

As illustrated in Figs. 9 and 10, where parts corresponding to those shown in Fig. 8 are designated by like reference numerals with the addition of a "prime" thereto, individual locking members of my locking means may be given such a contour as will result in an ornamental configuration when in their interlocking position; that shown in Fig. 2, and representing only one instance of the above, being heart-shaped.

My locking means is particularly suitable for use as a fastener for cartons or displays assembled from a blank form, but its use is by no means restricted thereto. Advantageous applications of my locking means in any desired number or forms may be found wherever the desire is to join a plurality of sheets of material, of such stiffness that the individual locking members can hold substantially their original contour while employed in an inter-locking capacity, and in such a manner that the individual sheets can be suitably tensioned or positioned to prevent unlocking of the resulting joint.

Whereas I have described my invention by reference to specific forms thereof, it will be understood that many changes and modifications may be made without departing from the spirit of the invention.

I claim:

1. A structure embodying a prepared blank of foldable sheet material, said blank comprising a series of panels related in integral sequence, locking means for joining certain of the said panels in effecting assembly of the structure, said locking means comprising at least one set of two individual locking members provided for mutual coordination, each locking member being formed integral with, and surrounded by, the sheet material of the blank, and each locking member, further, comprising both a male and a female formation, the male formation of one of a set of members being adapted for locking coordination with the female formation of the other of the set of members, so that the bases of the respective male members provide mutually limiting stops, the respective male members being of substantially equal extensions, and said individual locking members of the set being disposed in such relation to their respective panels that an edge of one of such panels lies parallel to and in abutting relation with the line of fold defining an edge of the other of such panels at which the latter is integrally related to the component structure.

2. A compartmented structure embodying a prepared blank of foldable sheet material, said blank comprising a series of panels related in integral sequence and folded in general spiral formation to provide compartments for the resulting structure, locking means disposed in a pair of contiguously positioned panels to secure such panels to each other and to retain the structure in assembled status, said locking means comprising at least one set of two individual locking members provided for mutual coordination, each locking member being formed integral with, and surrounded by, the sheet material of the blank, and each locking member, further, comprising both a male and a female formation, the male formation of one of a set of members being adapted for locking coordination with the female formation of the other of the set of members, so that the bases of the respective male members provide mutually limiting stops, the respective male members being of substantially equal extensions, and said individual locking members of the set being disposed in such relation to their respective panels that an edge of one of such panels lies parallel to and in abutting relation with the line of fold defining the edge of the other of such panels at which the latter is integrally related to the component structure.

3. A carton embodying a prepared blank of foldable sheet material, said blank having a peripheral configuration and fold lines across its body to form a set of serially, integrally related lateral panels and closure members for the carton extending respectively from the top and from the bottom of appropriate lateral panels, those individual lateral panels forming the free ends of the serial connection being mutually interlocked to resist unlocking during use and to provide a buttressing reinforcement for the resulting interlocked lateral panel of the final carton, the interlocking means comprising at least one set of two individual locking members formed respectively in the free ends of the serial connection of panels wholly within and spaced apart from the edges thereof, the individual locking members of any one set having a general tongue configuration, the free ends of the tongues being directed toward each other, the length of

the tongues being substantially equal, and the bases of the tongues being substantially equal in lateral extension, so that the joint, resulting from sliding one tongue under the other tongue and into the slit in the sheet material created by the provision of the latter tongue, and vice versa, until the respective bases of the tongues serve as mutually limiting stops, will effectively retain the structure in carton form during use and will afford readiness of disassembly to flat blank status, said individual locking members of any one set being disposed in such relation to their respective panels that an edge of one of such panels lies parallel to and in abutting relation with the line of fold defining the edge of the other of such panels at which the latter is integrally related to the component structure.

4. A compartmented carton comprising a prepared blank of foldable sheet material, said blank having a peripheral configuration and fold lines across its body to form a set of serially, integrally related body panels and closure members for the compartments extending respectively from the top and from the bottom of appropriate body panels, the said blank, further, being folded on itself in general spiral formation to produce the

desired number of compartments for the completed carton, locking means disposed in a pair of contiguously positioned panels to secure such panels to each other and to retain the structure in assembled status, said locking means comprising at least one set of two individual locking members provided for mutual coordination, each locking member being formed integral with and being surrounded by the sheet material of the blank, and each locking member, further, comprising both a male and a female formation, the male formation of one of a set of members being adapted for locking coordination with the female formation of the other of the set of members, so that the bases of the respective male members provide mutually limiting stops, the respective male members being of substantially equal extensions, and said individual locking members of any one set being disposed, in such relation to their respective panels, that an edge of one of such panels lies parallel to and in abutting relation with the line of fold defining the edge of the other of such panels at which the latter is integrally related to the component structure.

MARSHALL I. WILLIAMSON.
